UNITED STATES PATENT OFFICE.

PERLEY G. NUTTING, OF WILKINSBURG, PENNSYLVANIA, ASSIGNOR TO WESTINGHOUSE ELECTRIC & MANUFACTURING COMPANY, A CORPORATION OF PENNSYLVANIA.

MERCURY-ARC LAMP.

1,320,087.

Specification of Letters Patent.

Patented Oct. 28, 1919.

Application filed March 13, 1918. Serial No. 222,053.

To all whom it may concern:

Be it known that I, PERLEY G. NUTTING, a citizen of the United States, and a resident of Wilkinsburg, in the county of Allegheny and State of Pennsylvania, have invented a new and useful Improvement in Mercury-Arc Lamps, of which the following is a specification.

My invention relates to new and useful improvements in mercury-arc lamps and more particularly lamps of this character intended for laboratory purposes, and it has for its primary object, the provision of a mercury-arc lamp of increased efficiency because of structural features which increase the intensity of the light, prolong the life of the lamp and render its operation, without danger of injury to the eyes, convenient.

20 To the best of my knowledge, laboratory arc lamps heretofore employed have either been provided with bodies of fused quartz, rendering their use dangerous to the eyesight, or of glass of such a character as to require the use of water baths to keep them cool, by preventing formation of high-density vapors which would put out the arcs, the water-cooling rendering their employment inconvenient.

30 I have found that these difficulties may be overcome by providing means for air cooling and by forming the body of the lamp of hard glass and the leading-in wires and terminals of heavy tungsten wire. I have also found a simple and effective means for increasing the intensity of the light provided by the lamp.

In the drawing, the single figure of which is an elevation of a mercury-arc lamp constructed in accordance with my invention, is shown a tubular lamp body of substantially inverted U-shape, including an intermediate arc tube 10, a depending anode leg 11 and a depending cathode leg 12, each of 40 said legs being sealed at its lower end, about a heavy tungsten lead-in wire 13 having an inner tungsten terminal 14. Brazed or otherwise secured to the outer ends of the lead-in wires 13 are heavy copper connecting elements or terminals 15 to which the circuit conductors may be joined.

The cathode leg 12, intermediate its ends, has its internal diameter reduced to provide a constricted passage 16, for a purpose 45 which will be hereinafter specified. The

lower end of the cathode leg 12 is provided with a bulb-shaped enlargement 17 partially filled with mercury, while the anode leg 11 is substantially filled with mercury.

An air-cooling bulb 18 of suitable size 60 communicates, through a relatively large opening 19, with the intermediate portion of the arc tube 10. This entire body, including the arc tube, cathode and anode legs and air-cooling bulb 18, is formed of 65 hard glass that softens only at a high temperature.

I have found, from actual practice, that a mercury-arc lamp formed of such glass and provided with tungsten terminals, will 70 remain clean longer and give longer life than lamps made of soft glass and provided with platinum leading-in wires. In addition to this, the air-cooling bulb, if of the proper size and proportions, serves to control 75 the vapor pressure in the arc tube fully as well as a water bath and is, of course, much more convenient. Lamps of this type have been operated continuously for fifty hours without any sign of deterioration, a performance not approached 80 by any other lamps of this class of which I have knowledge.

The restricted passage 16 should be sufficiently large to allow mercury to drop 85 readily through it and yet small enough to condense the vapor that passes through it. A passage of approximately three millimeters in diameter has been employed with success, and the brilliancy and intensity of 90 the light provided by the lamp has been thereby materially increased.

It will, therefore, be clear that I have provided an improved form of mercury-arc lamp by providing an air-cooling structure, 95 by the employment of hard glass, by using tungsten lead-in wires and terminals and by constricting the passage of the cathode leg, to increase the light intensity.

Although I have illustrated and described 100 the various features of my improved lamp in considerable detail, it will be appreciated that no limitations, other than those set forth in the claims, are to be imposed upon my invention.

I claim as my invention:

1. A mercury-arc lamp including anode and cathode legs and a connecting arc tube all formed of hard glass that softens only at a high temperature, and tungsten lead- 110

ing-in wires and terminals sealed into the ends of the legs.

2. A mercury-arc lamp including anode and cathode legs and a connecting arc tube 5 all of hard glass that softens only at a high temperature, tungsten lead-in wires and terminals sealed into the ends of the legs, and air-cooling means associated with the arc tube.
- 10 3. A mercury arc lamp including anode and cathode legs, a connecting arc tube, and an air-cooled bulb having unrestricted com-

munication with the arc tube, all of such parts being formed of hard glass that softens only at a high temperature and the intermediate portion of the cathode leg having a constricted passage, and tungsten leading-in wires and terminals fused into the ends of the legs.

In testimony whereof, I have hereunto 20 subscribed my name this 28th day of Feb. 1918.

PERLEY G. NUTTING.
